CLAIM

The ornamental design for a vehicle tire, as shown and described.

DESCRIPTION

FIG. 1 is a front perspective view of a vehicle tire showing our new design.

FIG. 2 is a rear perspective view thereof.

FIG. 3 is a front elevational view thereof, with the rear elevational view, top plan view and bottom plan view being the same as FIG. 3; and,

FIG. 4 is a left side elevational view thereof, with the right side elevational view being a mirror image of FIG. 4.
